UNITED STATES PATENT OFFICE.

JOSEPH SOSS, OF NEW YORK, N. Y.

HINGE.

No. 804,561.

Specification of Letters Patent.

Patented Nov. 14, 1905.

Application filed March 6, 1905. Serial No. 248,435.

To all whom it may concern:

Be it known that I, JOSEPH SOSS, a citizen of the United States, residing at New York, in the county of New York and State of New York, have invented certain new and useful Improvements in Hinges, of which the following is a specification, such as will enable those skilled in the art to which it appertains to make and use the same.

This invention relates to invisible hinges for doors, gates, sashes, the lids and covers of boxes, cabinets, and the like, such as are shown and described in an application for Letters Patent of the United States filed by me February 16, 1905, Serial No. 245,809, and in United States Letters Patent granted to me December 8, 1903, No. 746,398; and the object of the invention is to provide means whereby a door or similar article provided with hinges of this class may be detached or disconnected from the frame or other holder with which it is connected without detaching the separate parts of the hinge.

The invention is fully disclosed in the following specification, of which the accompanying drawings form a part in which the separate parts of my improvement are designated by suitable reference characters in each of the views, and in which—

Figure 1 is a plan view of a hinge composed of two parts made according to this invention; Fig. 2, a section on the line 2 2 of Fig. 1; Fig. 3, a section on the line 3 3 of Fig. 2; Fig. 4, a front view of a hinge composed of three parts and provided with my improvement and showing the hinge closed, and Fig. 5, a back view of the hinge shown in Fig. 4 and showing the hinge open.

In the practice of my invention, as shown in Figs. 1 to 3, inclusive, I provide a hinge composed of two parts consisting of plates *a* and *b*, adapted, respectively, when the hinge is used as a door-hinge to be secured to the frame of the door and to the door, and in practice said plates are countersunk in the frame and door. The plates *a* and *b*, as in the application for United States patent hereinbefore referred to, are provided in their corresponding sides with oblong rectangular recesses *a*² and *b*², at the inner sides of which said plates are provided with inwardly-directed supplemental plates or members *a*³ and *b*³, which are segmental in cross-section and rectangular in form, and the plate or member *b*³ is provided at the top thereof with an outwardly-set segmental flange *b*⁴, forming a corresponding in-

ner segmental groove *b*⁵ on the inner side of the plate *b*³, while at the bottom of said plate *b*³ is an outwardly-set segmental flange *b*⁶, forming a segmental keeper *b*⁷ between said flange *b*⁶ and the plate *b*³ and on the outer side of said plate. The segmental plate *a*³ is provided at its upper end with an inwardly-set segmental flange *a*⁴, forming a segmental keeper *a*⁵, adapted to receive the flange *b*⁴ of the plate *b*³, and the segmental plate *a* is provided at its lower end with an inwardly-set segmental flange *a*⁶, adapted to enter the groove or keeper *b*⁷. In assembling the parts of this hinge the segmental plates, parts, or members *a*³ and *b*³ are slipped together, or the part, plate, or member *a*³ is dropped onto the part, plate, or member *b*³ and a screw or screws *x* are passed through the part, plate, or member *a*³ beneath the shoulder formed by the flange *b*⁴ of the part, plate, or member *b*³, as clearly shown in Fig. 2, and this prevents the separation of said parts by moving one vertically on the other, while permitting them to slide freely one upon the other. It is necessary also to provide means whereby these parts cannot be separated laterally in the operation of the hinge, and said parts *a*³ and *b*³ are provided, respectively, and near their free edges with an inwardly-directed lug or projection *a*⁸ and an outwardly-directed lug or projection *b*⁸ for this purpose, and these lugs or projections, as will be understood, prevent the separation of the parts *a*³ and *b*³ in the opening and closing of the door or other device.

If the hinge is intended for very light work, as when used in connection with small boxes, cabinets, or the like, the hinge is made by stamping the same from sheet metal and the lugs or projections *a*⁸ and *b*⁸ are formed by means of a punch or similar device; but if the hinge is intended for heavy work, as in the case of ordinary doors, the lugs or projections *a*⁸ and *b*⁸ may be formed in the process of casting or they may be formed by passing screws or similar devices through the parts *a*³ and *b*³.

In Figs. 4 and 5 I have shown a hinge of the class specified provided with my improvement and composed of three parts and similar to the hinge shown in the United States patent hereinbefore referred to. This hinge consists of three parts *c*, *d*, and *e*, and in practice the part *c* is secured to the door-frame and the part *d* to the door, while the part *e* is intermediate and connects the other parts and sup-

ports the door. The word "door" as here used is intended to designate any swinging or movable part, and the word "frame" to designate any stationary part. The part *c* 5 consists of an oblong plate *c*², provided at one side with a transversely-arranged oblong member *c*³, which is plano-convex in cross-section and the flat or plane face thereof being at right angles to the plane of said plate 10 and flush with one edge thereof, and at the back or convex side of the member *c*³ is an open space *c*⁴, which extends the full length of said member, and at the ends of said member *c*³ the back or convex side thereof is provided 15 with segmental flanges *c*⁵, forming segmental grooves or keepers *c*⁶. The part *d* consists of the plate *d*², one edge of which is provided with an oblong open space *d*³, at the back of which is a member or plate *d*⁴, which 20 is segmental in cross-section, and the upper end of the plate or member *d*⁴ is provided with an inwardly-set segmental flange *d*⁵, forming a segmental groove or keeper *d*⁶ on the inner side of the plate or member *d*⁴, and 25 said plate or member *d*⁴ is provided at its lower end with an inwardly-set flange *d*⁷, forming a segmental rabbet-groove *d*⁸ on the outer side of said flange. The part *e* of the hinge 30 consists of a plate which is segmental in cross-section and provided at the upper end with a thickened member *e*², having a segmental groove or keeper *e*³, and at its lower end with an inwardly-set segmental flange *e*⁴, forming a segmental groove or keeper *e*⁵, and 35 with an outwardly-set annular flange or rim *e*⁶, forming a segmental groove or keeper *e*⁷. The groove or keeper *e*³ opens downwardly, and the groove or keeper *e*⁵ opens upwardly, and the groove or keeper *e*⁷ is adapted to receive 40 the flange *c*⁵ on the part *c* of the hinge and the groove or keeper *e*⁷ to receive the flange or rim *d*⁷ on the part *d* of the hinge, while the groove or keeper *e*³ in the top of the part *e* of the hinge receives the top 45 flange *c*⁵ of the part *c* and *d*⁵ of the part *d*.

As thus constructed it will be seen that in assembling the separate parts of the hinge the part *e* is slipped into or onto the part or member *c*³ of the plate or part *c* of the hinge, 50 and the part or plate *d*⁴ of the part *d* is dropped into position on the part *e*, and in practice after the parts are thus connected a screw or screws *y* are passed through the top portion of the part *d*⁴ inwardly beneath the 55 annular shoulder at the top of the part *e* formed by the enlarged segmental head *e*², as clearly shown in Fig. 4, and these screws hold the parts of the hinge together and prevent any vertical movement of the part *d* on the part 60 *e*; but whenever it becomes necessary to detach the door for any reason all that is necessary is to remove the screw or screws *y* and lift the door off of the other parts of the hinge, the part *d* of the hinge remaining 65 secured to the door.

In practice the separate parts of the hinge, or the segmental members thereof, are provided with interlocking lugs or projections which prevent the separation of said parts in the operation of the hinge, as clearly shown 70 and described in the United States Letters Patent hereinbefore referred to; but said lugs or projections, which are clearly shown and described in said Letters Patent, form no part of this invention and are therefore not shown 75 or described herein, and the difference between the construction of the hinge shown in Figs. 4 and 5 and that shown in the United States Letters Patent hereinbefore referred to relate only to the bottom of the part *e* and 80 the bottom of the part *d*⁴ and to the screw or screws *y*, whereby the part *d* of the hinge may be lifted off of the part *e* and the door thus removed from the frame without detaching the hinge from the door and the frame. 85

In the construction shown and described in Figs. 1 to 3, inclusive, it will be observed that the outwardly-set segmental flange *b*³ at the bottom of the part *b*³ is formed on a circle of greater diameter than the outwardly-set flange or rim *b*⁴ at the top of said part *b*³, and the groove *b*⁵ at the top of the part *b*³ is therefore formed on a circle of less diameter than the groove or keeper *b*⁶ at the bottom of the part *b*³, and the same idea is involved in the 90 construction shown in Figs. 4 and 5, the flange *e*² at the top of the part *e* being formed on a circle of less diameter than the flange *e*⁶ at the bottom of said part, while the groove or keeper *e*³ in the top of the part *e* is formed 95 on a circle of less diameter than the groove or keeper *e*⁷ in the bottom of said part, and this construction enables the separate parts of the hinges to be properly fitted and also enables them to move easily and freely one 100 upon another. In practice the part *c*³ is provided on its convex side and at one edge thereof with a lug or projection *c*⁷, which operates in connection with a corresponding lug or projection *c*⁸ on the concave side of the part *e*, at 105 one edge thereof, to prevent the separation of said parts in the operation of the hinge, and the part *d*⁴ is provided on its concave side and at one edge thereof with a lug or projection *d*⁹, which operates in connection with a corresponding lug or projection *e*⁹ on the convex side of the part *e* and at one edge thereof and which prevents the separation of said parts in the operation of the hinge, all these features 110 of construction being similar to those described and claimed in the United States Patent hereinbefore referred to. It will also be observed that the flanges *b*⁴ and *b*⁶ at the top and bottom of the part *b*³ in the construction shown in Figs. 1 to 3 are upwardly-directed flanges, and the flanges *e*² and *e*⁶ at the top and bottom of the part *e* in the construction shown in Figs. 4 and 5 are also upwardly-directed flanges, while the flanges at the top 115 and bottom of the part *d*⁴ in the construction 120

125

130

shown in Figs. 1 to 3, inclusive, are downwardly-directed flanges, as are also the flanges at the top and bottom of the part d^4 in the construction shown in Figs. 4 and 5, and without this arrangement or construction the separate parts of the hinge could not be connected and disconnected, as hereinbefore described.

My invention is not limited, however, to the exact form of invisible hinges herein shown and described, and various changes in and modifications of the parts of the hinge by which said parts may be connected and disconnected may be made without departing from the spirit of my invention or sacrificing its advantages.

Having fully described my invention, what I claim as new, and desire to secure by Letters Patent, is—

1. A hinge, comprising a plurality of segmental members movable one upon another, one of said members being provided at one end thereof with an outwardly-set flange forming a segmental groove and at the other end thereof with an outwardly-set flange forming a segmental keeper, the last-named flange and keeper being formed on a circle of greater diameter than the first-named flange and groove; and another of said parts being provided at one end with an inwardly-set flange forming a segmental keeper adapted to receive the first-named flange of the first-named part and at the other end thereof with an inwardly-set segmental flange adapted to enter the keeper of the first-named part, said parts being adapted to be connected by moving one longitudinally of the other, substantially as shown and described.

2. A hinge, comprising a plurality of segmental members movable one upon another, one of said members being provided at the top thereof with an outwardly-set flange forming a segmental groove and at the bottom thereof with an outwardly-set flange forming a segmental groove or keeper, the flange and groove

or keeper at the bottom of said member being formed on a circle of greater diameter than the flange and groove at the top of said member; and another of said parts being provided with an inwardly-set and downwardly-directed segmental flange or rim forming a segmental keeper adapted to receive the flange or rim at the top of the first-named part and at the bottom thereof with an inwardly-set and downwardly-directed segmental flange or rim adapted to enter the groove or keeper at the bottom of the said first-named part, substantially as shown and described.

3. A hinge, comprising a plurality of segmental members movable one upon another, one of said members being provided at the top thereof with an outwardly-set flange forming a segmental groove and at the bottom thereof with an outwardly-set flange forming a segmental groove or keeper, the flange and groove or keeper at the bottom of said member being formed on a circle of greater diameter than the flange and groove at the top of said member; and another of said parts being provided with an inwardly-set and downwardly-directed segmental flange or rim forming a segmental keeper adapted to receive the flange or rim at the top of the first-named part and at the bottom thereof with an inwardly-set and downwardly-directed segmental flange or rim adapted to enter the groove or keeper at the bottom of the said first-named part, and means to prevent the vertical movement of said parts one upon another, substantially as shown and described.

In testimony that I claim the foregoing as my invention I have signed my name, in presence of the subscribing witnesses, this 1st day of March, 1905.

JOSEPH SOSS.
